UNITED STATES PATENT OFFICE.

WILLIAM C. DUST, OF ST. LOUIS, MISSOURI.

CAR-CONTROLLING APPARATUS.

1,171,109.

Specification of Letters Patent. Patented Feb. 8, 1916.

Application filed June 19, 1915. Serial No. 35,113.

To all whom it may concern:

Be it known that I, WILLIAM C. DUST, a citizen of the United States, residing at St. Louis, in the county of St. Louis City and State of Missouri, have invented certain new and useful Improvements in Car-Controlling Apparatus; and I do hereby declare the following to be a full, clear, and exact description of the invention, such as will enable others skilled in the art to which it appertains to make and use the same.

This invention relates to new and useful improvements in car controlling apparatus, and has for its principal object to provide a device which will simultaneously cut off the power and apply the brakes to a motor car by operating a single foot pedal.

Another object of the invention is to provide a device which will also drop a trip member and permit the sand in the box of the car to fall upon the tracks and thereby increase the friction of the wheels.

A further object of the invention is to provide a device which is air-operated and which will return to its normal running position at the desire of the user.

Still another object of the invention is to provide a novel means for controlling the flow of current to the motor which insures the perfect contact at all times.

With these and other objects in view the invention consists in the novel combination and arrangement of parts which will be fully set forth in the following specification and accompanying drawings, in which,

Figure 1 is a top plan view partly in section of a controlling mechanism constructed in accordance with this invention and showing the same ready to be applied to a car of the usual construction, Fig. 2 is a view illustrating the device as it would appear when attached to the car, Fig. 3 is a wiring diagram illustrating the circuit controlling means, Fig. 4 is an enlarged fragmentary view of Fig. 1 showing the switch, and Fig. 5 is an enlarged detail sectional view showing the controlling pedal.

Referring now to the drawings by characters of reference, the numeral 1 designates as an entirety the body of the car which rests on the usual frame 2. This frame carries the usual journal boxes 3 in which the axle 4 is journaled. Secured to the axles in the usual manner are the wheels 5 which are connected to the motor in any suitable way and are arranged to be driven thereby. The

forward platform is designated by the numeral 6 and is provided with the usual guard 7 and bumper 8 as clearly shown in Fig. 2.

Secured beneath the car frame 2 is the frame of the mechanism which is designated by the numeral 9 which comprises the side bars 10 and end bars 11. Secured to one of the end bars centrally of the side bars is the cylinder 12 in which the piston 13 is slidable. This piston is provided with the usual piston ring 14 and carries the piston rod 15, the outer end of which is connected to the sliding bar 16 which extends transversely of the frame and projects through the slot 17 formed in one of the side bars. An angular extension 18 is formed on the free end of the projected end of the bar 16 and this extension is connected in any suitable manner to the valve 19 of the sand box 20.

In order that the sand within the sand box may be loosened and prevented from becoming caked there is an upright member carried by the slide 19 which travels through the box upon movement of the slide and engages the sand, thus loosening the same and causing it to flow through the desired opening.

A forwardly extending rod 21 is secured to the bar 16 in direct alinement with the piston rod 15 and this bar is slidable between the guide rods 22 in which the cross head 23 is arranged to slide.

Slidably vertically in the forward end 11 of the frame is the plunger designated generally by the numeral 24 which comprises the body 25 which is slidable in the frame 26. This frame 26 is connected to the frame 9 at its forward end and supports the plunger mechanism. A suitable aperture 28 is formed in the plunger 25 near its upper end and is designed to permit the forward end of the bar 21 to pass therethrough. Secured to the lower end of the slide 25 is the tubular member 27 which is designed to slide on the stem 29 which is carried by the lower end of the frame. An upwardly extending stem 30 is formed on the upper end of the slide 25 and this stem terminates in the foot pedal 31 which is disposed above the platform of the car.

A pair of cylinders 32 are secured to the forward end 11 of the frame 9 and slidable in these cylinders are the pistons 33 to which the piston rods 34 are secured. These piston rods are fastened in any suitable man-

ner at their opposite terminals to the bar 16 and are arranged to act in a direction opposite to the action of the piston rod 15 hereinbefore mentioned.

- 5 The end of the bar 16 opposite the angular extension 18 is connected as at 35 to the sliding bar 36. These two bars are insulated from each other as at 37 and the sliding bar is slidably mounted in the guide 10 bars 38 which are insulated as at 39 from the frame 9. These guides are also insulated from the guide 40 to which the binding post 41 is secured. This binding post 41 is arranged to form the electrical contact for the bar 36 and the end of the bar opposite the one which is slidable in the guide 38 is arranged to slide in the guides 42 which are spaced from the guide 40 and are provided with the binding post 43, which is arranged 15 to energize the plate 44, which plate is provided with the lug 45 around which the spring 46 is coiled. This spring 46 is arranged to exert pressure against the plate and force the same toward the lug 47 and 20 against the end of the contact bar 36 when the same is in its normal position. It will thus be seen that a device is provided which will throw in or throw out an electrical circuit according to the position of the contact 25 bar 36 and arm 16.

Secured intermediate the ends of the bar 21 is the clamp member 49, which clamp member is arranged to be removably secured to the bar and support the rearward extension 35 48, which is slidable through the bracket 50. This arm 48 terminates in the downwardly extending member 51 which is designed to engage the upper bar 52 of the trip fender designated generally by the 40 numeral 53. This trip fender is pivoted as at 54 and the horizontal portion 55 thereof is arranged to be lowered when the arm 48 slides forwardly. This trip fender is normally held upwardly when the bar 16 is in 45 the rearmost position as shown in Fig. 1, and this position is also clearly illustrated in Fig. 2.

In wiring the device in order to cut out the electrical circuit, the usual trolley wire 50 designated by the numeral 57, is provided on which the trolley wheel 58 is arranged to run. This trolley wheel is secured to the usual trolley pole 59 which is connected at 55 60 to the wire 61 which carries the circuit to the binding post 43. The current then passes from the binding post 43 through the bar 36 and the binding post 41 into the wire 62, from whence it passes into the controller designated generally by the numeral 63, and 60 thence out through the wire 64 to the motor 65, from whence the same passes through the wire 66 to the ground designated by the numeral 67. It will thus be seen that an 65 effective cut-out for the power supply is provided which will be operated upon move-

ment of the bar 16 in a forward direction. In order to prevent the lighting system of the car from being affected, the wire 68 is connected at 69 to the wire 61 at a point intermediate the point 60 and the binding post 43, and this wire 68 is connected to the lamp jacket 70, the opposite terminal of which is connected to the wire 71. This wire 71 is provided intermediate its ends with the resistance means designated by the 75 numeral 72 and the switch designated by the numeral 73. The opposite end of the wire is connected as at 74 to the ground 70 through the wire 66, and it will thus be seen that a complete short circuit through 80 the lighting system is provided which is not at all affected by the operation of the motor.

In order that the operation of the device may be positive, the air from the air brake system is used and passes from the reservoir 85 75 through the valve 76 into the pipe 77 and thence through the pipe 78 and check valve 79, into the cylinder 12 and behind the piston 13. A suitable blow-off check valve 80 is provided to prevent the pressure within the cylinder 12 from becoming excessive, and when the operator presses his foot upon the pedal 31 it will be apparent that the member 24 will descend until the aperture 28 comes into alignment with the end of the 90 rod or bar 21. This will permit the bar to slide forward under the influence of the air pressure in the cylinder 12 against the piston 13 until the limit of power has been reached, which will simultaneously force the 100 bar 16 forwardly, thereby allowing the sand carried in the box 20, to pass through the pipes and on to the track. Simultaneously with this movement the power is cut off by the bar 36 disengaging the plate 44 and when the piston has reached its limit of travel the outlet pipe 81 will be uncovered which will permit the air to pass through the check valve 82 and into the pipe 83, from whence it will pass into the brake cylinders 110 of the car and thus apply the brakes. The air passing into the cylinder 12 will also pass into the pipe 84 and thence forwardly through the valve 85 to the indicator designated by the numeral 86, thereby plainly indicating to the controller of the vehicle the amount of air pressure within the cylinder. After the car has been brought to a stop the lever 87 of the valve 85 is thrown in such a position as to open the valve and 115 permit the air within the cylinder to flow through the exhaust pipe 88 and thus to the atmosphere. Simultaneously with this movement the valves 89 are opened which will permit the air from the reservoir 75 to pass through the pipe 90 and into the cylinders 32, which cylinders will force the bar 16 back to its normal position and thereby reset the mechanism, thus permitting the 120 car to proceed. Simultaneously with the 125 130

rearward movement of the lever 16 and rod 21, the plate 48 is forced rearwardly and then the trip member 53 is raised to the position illustrated in Fig. 2.

It will thus be seen that a particularly simple and effective device is provided which may be controlled from a single foot pedal and which will effectively bring a car to a standstill in a relatively short distance.

While in the foregoing there has been shown and described the preferred embodiment of this invention, it is to be understood that such changes may be made in the combination and arrangement of parts as will fall within the spirit and scope of the invention as defined in the appended claims.

What is claimed is:

1. The combination with an electric motor car, of a frame secured beneath the car, cylinders in the frame, one of said cylinders being in constant communication with an air reservoir, a bar slidable in the frame, a piston within the cylinder, said piston being connected to the bar and arranged to slide the same longitudinally of the frame, a rod extending forwardly of the bar, a slide limiting the movement of the rod and holding the same against the air pressure in the cylinder, said slide being arranged to be manipulated to permit the rod to slide forwardly, means carried by the bar to control a flow of current through the electric motor of the car, and means connecting the opposite cylinders with the bar and with the air supply, and a valve arranged to relieve the main cylinder of its air pressure and permit the auxiliary cylinder to force the bar to its normal position.
2. The combination with an electric motor car, of a frame supported beneath the car, a main cylinder mounted within the frame, a pair of auxiliary cylinders mounted in the frame, a bar slidable longitudinally in the frame, said bar being connected to the cylinder and arranged to be operated thereby, a rod extending forwardly of the bar, said rod being in direct alinement with the main cylinder, means connecting the main cylinder with the air reservoir to maintain a pressure therein, means to relieve the pressure within the main cylinder, electrical contacts carried by the car and arranged to break the circuit through the motor, a foot pedal controlling the operation of the forwardly extending bar to permit the same to slide forward under the influence of the air pressure in the main

cylinder, and valves controlling the flow of air through the auxiliary cylinders to return the bar to its normal position.

3. The combination with an electric motor car, of a frame mounted within the car, a main cylinder within the frame, a piston slidable in the cylinder, a pair of auxiliary cylinders in the frame, pistons in the auxiliary cylinders, a bar slidable longitudinally of the frame, means connecting the bars with the pistons of the cylinders, the main cylinder working in a direction opposite to the auxiliary cylinders, a pipe connecting the main cylinder with the air reservoir of the air brake system to normally maintain a pressure within the cylinder, a forwardly extending rod connected to the bar in direct alinement with the main cylinder, means limiting the forward movement of the forwardly extending bar and arranged to permit the bar to slide forward when so desired, a valve to relieve the air pressure within the cylinder, and valves controlling the admission of air to the auxiliary cylinders to force the bar rearwardly to expel the air from the main cylinder.

4. The combination with an electric motor car having an air brake system, a motor, a trip fender, and a sanding device, of a frame secured to the car, a main cylinder mounted within the frame, said main cylinder having an inlet port at one end and an outlet port substantially centrally thereof, the inlet port being connected to the air reservoir of the air brake system, the outlet port being connected to the brake cylinder, a bar slidable longitudinally of the frame, means carried by the bar to control the operation of the sanding device, means carried by the bar to control the supply of electric current to the motor, oppositely acting cylinders mounted in the frame, a rod extending forwardly of the bar, means controlling the movement of the forwardly extending rod, a constant air pressure maintained within the main cylinder to normally force the rod and bar forwardly, and means to relieve the pressure therein and allow the air to enter the opposite cylinder to return the bar to its normal position, and means connected with the forwardly extending rod to control the operation of the trip fender.

In testimony whereof I affix my signature in presence of two witnesses.

WILLIAM C. DUST.
